UNITED STATES PATENT OFFICE.

MAX P. HERMANN, OF PHILADELPHIA, PENNSYLVANIA.

SURGICAL-INSTRUMENT HOLDER.

No. 867,727.

Specification of Letters Patent.

Patented Oct. 8, 1907.

Application filed June 14, 1907. Serial No. 378,951.

To all whom it may concern:

Be it known that I, MAX P. HERMANN, a citizen of the United States, residing in the city and county of Philadelphia, State of Pennsylvania, have invented 5 a new and useful Surgical-Instrument Holder, of which the following is a specification.

My invention consists of a surgical instrument holder embodying a device with which such instruments are connectible, and on which they are adapted to be folded and retained in compact form, while being also 10 sheathed or covered, so as to be convenient for carrying, etc.

It also consists in rendering the instruments removable, and adapting them to be attached to a handle, 15 so as to be in proper and reliable condition for operation, details of construction being presented also, as will be hereinafter described.

Figure 1 represents a side elevation of a sheath or casing of a holder embodying my invention, the opposite ends of said holder appearing at the relative parts of said sheath. Fig. 2 represents a side elevation of the holder, and a longitudinal section of the sheath. Fig. 3 represents a side elevation of the holder, the instruments thereon being in different positions from 20 those shown in Fig. 2. Fig. 4 represents a longitudinal section of a portion of the device. Fig. 5 represents a transverse section on line x—x, Fig. 4. Fig. 6 represents a longitudinal section of a handle, with which an instrument is connected. Fig. 7 represents an end 25 view of the handle.

Similar letters of reference indicate corresponding parts in the figures.

Referring to the drawings:—A designates a stock or bar, to the ends of which are secured the heads, respectively, B, C. To each head there are pivoted the sockets D, which are internally threaded, to receive the threaded ends E of the shanks F of the instruments G, it being noticed that said sockets and said instruments are adapted to be folded on said bar A in the longitudinal direction of the same, as shown in Fig. 2. The bar A is channeled in the direction of its length, forming the pocket H, in which may be located the handle J for an instrument when in use, as shown in Fig. 6.

K designates racks, which are secured to the bar A and extend around the same, so as to receive the shanks of the instruments, they being somewhat resilient in their nature, so as to create pressure on said shanks and so hold the instruments in folded positions on the bar A, it being noticed that in the folded position of 50 the parts, the device is placed in the sheath or casing L, whereby the instruments are inclosed, and improper contacting with the same is prevented. In order to retain the device in said sheath, the head B is provided with the threaded stub M, see Fig. 4, the same projecting outwardly from said head in the longitudinal direction of the bar A. On said stub is

fitted the collar N, whose side is split or divided, so as to form the resilient tongues P, on the terminals of which, on the exterior thereof, are the shoulders Q, which are adapted to bear against the adjacent inner 60 portion of the sheath L and engage the shoulder R at the end of the latter.

In order to tighten the collar against sheath L, I employ the nut R', which is adapted to be screwed upon the stub M and bear against the adjacent outer edge of 65 the tongues P and pressing the shoulders Q thereof outwardly against the shoulder R, thus securely locking contacting parts and preventing improper removal of the holder from the sheath.

The holder J consists of the casing S, within which is 70 the rotary stem T, one end of which is provided with the socket U, which is within said casing, and the other end is provided with a milled head V, which is adapted to bear against and rotate on the adjacent end of said casing.

The end of the casing opposite to the head V has an opening W therein, the same being adapted to receive the shank of an instrument G, while the threaded end E thereof enters the socket U and may be screwed thereto, as has been stated.

The shank of the instrument is provided with a shoulder X, which is adapted to contact with the adjacent end of the casing T, it being evident that when the head V is rotated, motion is communicated to the socket U to rotate the same, when as said socket engages with the threaded end of the instrument, said end is drawn into the socket and the shoulder X tightened against the end of the casing T and so connected with the handle J, when the instrument is firmly held by the latter and is in condition for operation.

In order to prevent rotation of the instrument on the handle, the opening W in the casing T is oblong, and a corresponding portion of the shank of the instrument is similarly shaped, as at Y. By this provision, 95 the shank is controlled by the walls of the opening W and so prevented from being turned by the rotation of the socket U or from turning on the handle.

The sockets D are pivoted to the heads B, C, as has been stated, and their axes consist preferably of the 100 piece Z of wire, which is passed through eyes of said sockets in circular form, and its ends are united by twisting or other means, as are plainly shown in Fig. 5.

While I have specified certain means for carrying out my improvements, I do not wish to be limited exactly to the same, but desire to make such changes as may come within the scope of the novelty involved.

Having thus described my invention, what I claim as new and desire to secure by Letters Patent, is:—

1. An instrument holder embodying a stock, a socket pivotally connected therewith, and an instrument adapted to

- be removably connected with said socket and folded with the holder on said stock.
2. In an instrument holder, a stock, an instrument adapted to be pivotally connected therewith and folded 5 thereon, and a device on said stock for retaining the instrument in folded condition.
3. In an instrument holder, a stock, an instrument adapted to be pivotally connected therewith and folded thereon, and a resilient device on said stock for retaining 10 the instrument in folded condition.
4. In an instrument holder, a stock, a socket pivotally connected therewith, and an instrument adapted to be secured to said socket, said socket and instrument being foldable on said stock.
- 15 5. In an instrument holder, a stock, a socket pivotally connected therewith, and an instrument, said socket being threaded and said instrument having a threaded member adapted to engage the threads of said socket.
6. In an instrument holder, a socket, a support with 20 which the same is pivotally connected, an instrument having a threaded shank adapted to be screwed to said socket, and a shoulder on said shank, the latter having flattened or oblong sides.
7. In an instrument holder, a stock, means for pivotally 25 connecting an instrument therewith, and a handle for said instrument, said stock having a chamber adapted to receive said handle.
8. In an instrument holder, a stock, a head thereon, an instrument adapted to be pivotally connected with said 30 stock, an expandible tongue on said head, a sheath for the
- holder and the instruments, and means on said head for engagement with said tongue to press it against the adjacent portion of said sheath.
9. In an instrument holder, a stock, a head thereon, a screw projecting from said head, an expandible tongue, means for carrying said tongue on said head, a sheath for the holder and the instruments, and a nut fitted on said screw adapted to engage said tongue and force it into locking engagement with the adjacent portion of said sheath. 40
10. In an instrument holder, a sheath therefor, a collar fitted on said holder, said collar having a divided side forming a resilient tongue, a shoulder on said sheath adjacent to said tongue, and means on the holder for forcing said tongue into engagement with said shoulder. 45
11. In an instrument holder, an instrument adapted to be detachably connected therewith and folded thereon, and a handle for said instrument being adapted to have said instrument attached thereto and clamped therewith.
12. In an instrument holder, an instrument having a flattened or oblong shank, and a handle for said instrument having an opening to receive said shank, and means for firmly clamping the instrument to said handle, said opening being flattened or oblong, corresponding to that of the instrument. 50
